PUMPING APPARATUS

Alfred Charles Page, Detroit, Mich., assignor to
 Chicago Pump Company, Chicago, Ill., a corporation of Illinois

Application August 24, 1939, Serial No. 291,646

12 Claims. (CL 103—3)

This invention relates to pumping apparatus and particularly to that type utilizing pumps to handle sewage or trade wastes containing suspended solids such as rags, waste or stringy materials and other solids which may clog the impeller of the pump.

One object of the invention is to provide means to cause a reversal of flow through parts of the system to flush certain strainers in which the solids are collected when the pump is operating.

Another object is to provide auxiliary control means whereby when the pump is operating for a period of time, certain valve mechanism of the control means will be reversed to cause the stream of water containing the suspended solids to change its flow from one strainer to the other and for a reverse flow to occur through the strainer which first received the flow for a period of time.

Another object is to provide a motor driven valve mechanism to reverse the flow through the strainers, together with an electric circuit whereby when the pump motor is operating normally, for periods of less than certain predetermined ones, for example less than ten minutes, the valve motor will remain idle, but when the pump motor stops, the valve motor will operate and rotate the valve to direct the flow through a reversed direction.

With these and other objects and advantages in view, this invention consists in the several novel features hereinafter fully set forth and claimed.

One embodiment of the invention is clearly illustrated in the drawings accompanying this specification, in which:

Fig. 1 is a vertical cross-section through a pump pit showing a wet well to collect the liquid and a dry pit to receive the pump and associated parts, the pumping apparatus being shown in side elevation.

Fig. 2 is an end elevation of parts of the pump, valve and piping shown in Fig. 1, but showing the valve mechanism in section to show the interior construction.

Fig. 3 is an elevation partly in section of a worm and worm wheel for actuating the valve.

Fig. 4 is a central longitudinal sectional view through the valve and worm wheel.

Fig. 5 is a central vertical section through one of the strainers, and

Fig. 6 is a diagrammatic view of the wiring and control apparatus.

Referring to the drawings, which are merely illustrative of one form of the invention, 10 indicates a sewer or waste pipe from an industrial plant and this pipe is provided with a shut-off valve 11 of the gate valve or shear gate type as may be desired. The reference character 12 des-

ignates a wet well into which the liquid from the pipe 10 empties.

The wet well is formed by a retaining wall 13, a separating wall 14 and bottom 15. A dry pit formed of the retaining wall 16, bottom 17 and the separating wall 14 is located adjacent the wet well and this dry pit contains the pump, piping, strainers and valve mechanism forming the subject matter of this invention.

The separating wall 14 is provided with two wall pipes 18 which are arranged side by side in spaced relation (see Fig. 2) and in the same plane. In Fig. 1, the second wall pipe 18 is located directly behind that shown. These wall pipes receive extension pipes 19 to which check valves 20 are connected through flexible fittings 21. U bends 22 are connected to the check valves and have their upper ends connected to T fittings 23. A base member of a strainer 24 (see Fig. 5) is connected to the upright branch of each T fitting 23, and this base member is provided with an annular groove 25 machined in the inside wall to receive a gasket 26 that impinges against the shell 27 of the strainer housing. The base member is also machined to receive the flange 28 of a perforated or otherwise formed strainer 29.

A valve 30 having a housing 30a (see Figs. 1, 2 and 4) is provided with two horizontally disposed elbow hubs 31 to which the strainer housing shells 27 are attached, and said valve housing is also provided with two vertically disposed hubs 32 and 33. The upwardly directed hub 32 flares outward and terminates in a flange 34 to which the volute chamber of pump 35 is connected. This connection is to the suction side of the pump 35, and the discharge from the volute chamber terminates in the elbow 36 which is directed downwardly to receive the single connecting discharge pipe 37. A U-bend 38 connects the discharge pipe 37 with the flanged hub 33 that extends downwardly from the valve housing 30a. A valve plug 39 rotatably mounted in the valve housing 30a is provided with two ports 40, 41, and is arranged in one position to have the port 40 connect the strainer housing shell 27 through the flanged hub 31 of the piping on "A" side of the apparatus, with the suction side of the pump, while port 41 connects the discharge from the pump through the hub 33 to the strainer housing shell 27 of piping on "B" side of the apparatus. Rotation of the valve plug through 90° reverses the flow through the strainers.

The straight through flanges of the two T's 23 are connected through adapters and flexible fittings and check valves 42 to elbows 43 that lead to a T fitting 44, the upright branch of which connects with a common discharge pipe 45.

The pump volute casing is connected to the cover plate 46 of the pump and this cover plate is attached to the hanger pipe 47 which has its

upper end attached to the floor plate 48 upon which the motor pedestal 49 is mounted. An electric motor 50 is mounted upon the motor pedestal and drives the pump through the shaft 50a. The pump construction is of the typical centrifugal type having an impeller mounted within the volute chamber, and the extension shaft 50a rises through the hanger pipe and intermediate bearings to the place where it is connected through a coupling to the motor shaft, as is customary.

The valve plug 39 is mounted upon a shaft 51 (see Fig. 4) which has a bearing 52 in the rear wall of the valve housing 30a and a forward bearing in a removable cover plate 53 which may be bolted to the flange of the valve housing 30a. A stuffing box 54 is provided in this cover plate and a gland 55 may be tightened when it is desired to take up on the packing to prevent leakage around the shaft. A worm wheel 56 is mounted upon the shaft 51 and is enclosed in a housing 57 so that lubricant may be supplied to the gear and to prevent drippings and other harmful agents from damaging the gearing. A worm 58 meshes with this worm wheel 56 and this worm is carried by a vertical shaft 59 which is journaled in bearings carried by the worm gear housing 57.

The vertical shaft 59 extends upwardly to the coupling 60 (see Fig. 6) and is connected to the motor shaft 61 of a valve motor 62. The motor 62 is mounted upon a housing 63 and this housing encloses a second worm wheel 64 which is mounted upon a cross shaft 65 journaled in bearings carried by the housing 63. A worm 66 carried by the vertical shaft 59 meshes with the worm wheel 64 and the ratio of the worm 66 and worm wheel 64 to the worm 58 and worm wheel 56 is four to one. That is, while worm wheel 64 is making one revolution, worm wheel 56 is making one quarter revolution.

A roller 67 is mounted upon the worm wheel 64 and in certain position of the worm wheel this roller engages an arm 68 of a trip to swing a bracket 69 and thereby tilts a circuit breaker to stop the operation of valve motor 62 as will be hereinafter described.

A float guide pipe 70 is located in the wet well and may be suspended from the basin cover 71. This guide pipe is open at the top so as not to entrap any air within the pipe which might prevent free rising and falling of the liquid level within the pipe. A float 72 is slidably mounted upon a float rod 73, and adjustable buttons 74 and 75 are carried by this float rod so that the desired range of float movement may be had with respect to the float rod. A smaller pipe 76 serves to guide the float rod in its up and down movements and this pipe is attached to the under side of a floor plate 77 upon which a standard 78 is mounted. A lever 79 is carried by this standard and has its free end connected to the float rod 73 by links 80 and a clevis 81. The lever 79 carries a bracket 82 in which two circuit breakers or contactors 83 and 84 are mounted. A rod 86 extends from the hub of the lever 79 and carries a counter weight 86a which may be shifted as is necessary to balance the weight of the pendant float rod.

As liquid accumulates in the wet well, the level therein rises and the float 72 rises on the float rod 73 until the float contacts the button 74 on the float rod. Then, continued upward movement of the float raises the float rod until the lever 79 has been swung to tilt the contactors 83

10 and 84 to the opposite position of that shown in Fig. 1, thereby closing the starter circuit for the pump motor 50. When this happens, the pump motor 50 starts and the pump draws liquid 15 from the wet well through the piping and strainer that then leads through the valve 30 to the suction side of the pump, and discharges it through the other strainer, and finally through the discharge pipe 45 up to and through the elbow at the top thereof and the piping ultimately connected thereto.

By referring more specifically to Fig. 6, the electrical equipment and sequence of operations may be more fully understood. When the float rod 73 rises, it swings lever 79 and tilts contactors 83 and 84 to a position opposite to that shown in Fig. 6. Preferably the contactors are of the mercury switch type. When contactor 84 is swung over, the mercury flows to the other end and closes the circuit through the terminals therein. When it is desired to operate certain members of the electrical equipment at a lower voltage than that supplied through the line 85 a transformer is used for such members of the 20 electrical equipment. Then, current from the main line 85 flows through the main line switch S and to a starter panel 87 where lines from two of the leads run to the primary winding 88 of the transformer. The secondary winding 89 of 25 the transformer feeds a circuit through line 90 to a tap which leads to solenoid 91 and then through thermal overload circuit breakers 92, and then to one of the terminals of contactor 84. From the other terminal of contactor 84, the 30 circuit leads back to wire 93 which returns to the secondary of the transformer. When this circuit is completed, the solenoid 91 actuates its rocker arm and closes the contactors 94 of the starter, thereby closing the motor circuit and the motor 35 40 45 50 starts operating, thereby driving the pump. When the level of the water in the wet well falls, the float 72 drops and as it contacts the button 75, it causes the float rod to lower and continue until the switch lever 79 is swung to the position shown in Fig. 6, at which time contactor 84 tilts back and causes the mercury to flow from the terminals to open the circuit through solenoid 91 when the rocker arm swings to open the contactors 94 of the starter, and the pump motor 50 stops.

The electrical equipment just described comprises one means for starting and stopping the pump motor, which is responsive to liquid level changes in the wet well. Means are provided 55 to start and stop the valve motor after the pump motor has stopped. One means will now be described:

While contactor 84 is tilted to open the circuit through it, contactor 83 is tilted to close the circuit through its terminals, and the pilot circuit, controlled by contactor 83, then is through wire 90 and wire 95 to one of the terminals of the contactor 83 and then from this contactor through wire 96 to solenoid 97 and on to wire 98 which connects to wire 93. When the solenoid 97 is energized, the armature lifts a pawl 99 which rotates a ratchet wheel 100, one quarter revolution. This swings a bridge 101 of a four pole switch 102 to connect the now open contacts thereof, and when the four pole switch is closed in this position, a circuit then is completed from wire 95 to wire 103, through the live points of switch 102 and through wire 104 and on to a second four pole switch 105. With the bridge 106 of the second four pole switch 105

set to contact wire 104, the circuit then continues through the bridge to wire 107 and on to a motor starting solenoid 108 and through wire 108 back to wire 88 and to the secondary of the transformer. When the solenoid 108 is energized, the rocker of starter 110 for motor 62 is moved to close the contacts to complete the circuit from the main line to the valve motor 62. The valve motor 62 then operates to rotate the vertical shaft 59 to rotate the valve plug 38 one quarter turn to thereby reverse the direction of flow through the strainers. While the valve plug is making its quarter turn, worm wheel 64 makes a complete turn so that at the completion of its rotation the roller 67 engages the arm 68 of the circuit breaker and swings bracket 69 to tilt the contactor 70 to cause the mercury to flow toward the terminals where it closes a circuit from wire 88, through wire 111 to the contactor 70 and then through wire 112 to solenoid 113 and on through wire 114 to wire 88 and back to the secondary of the transformer. When solenoid 113 is energized, the armature is lifted and through the pawl 115 the second four pole switch 105 is actuated to cause the bridge to connect wire 116 to wire 107. This opens the circuit to solenoid 108 and the contactors of starter 110 are opened to stop the valve motor 62. The next time that the float rod is lowered and the solenoid 97 is energized, the bridge 101 will be rotated to contact wire 116 to again actuate starter 110 to operate motor 62.

With this electrical control equipment, in one position of lever 78, the pump motor runs, and in the other position the pump motor is idle and the valve motor runs until the valve has been rotated one quarter turn to reverse the direction of flow through the strainers. Should the four pole switches 102 and 105 accidentally be out of cycle, it will require an extra movement of arm 79 to again bring them into cycle, but when the electrical equipment is once started, these two four pole switches trail one another properly.

A further provision is made to reverse the flow through the strainers one or more times when the pump motor runs for longer periods of time than normally, due to greater inrushes of liquids or sewage due perhaps to storms or other unforeseen conditions. During such long periods of operation, it is desirable to reverse the flow through the strainers, one or more times during continued operation of the pump, to clean the accumulated solids from the system and to pass them on through the discharge pipe. For accomplishing this result, a time clock or other time controlled mechanism is provided to allow a predetermined length of time for operation of the pump motor and then to cause one or more valve movements to reverse the flow. In the form shown, a time clock 117 is employed in which the winding 118 of the motor is connected to wire 88 through a wire 119 and through a contactor in the starter 87 so that when the rocker arm of the starter is actuated to close the circuit through the pump motor, the circuit for the time clock is also closed. From this contactor of the motor starter a wire 120 leads to the motor winding 118 and from this winding, a second wire 121 leads back to wire 88 to complete the circuit. Closing the circuit just described starts the time clock motor. The time clock circuit is split and from wire 120 a lead passes to a solenoid 122 and from this solenoid, a wire leads to wire 121 to complete this circuit.

The time clock has a train of speed reducing gears 123a, the last one of which may comprise a friction disc 123. When the solenoid 122 is energized it rocks a yoke 123b, which carries the final friction roller 123 of the gear train so that the friction roller 123 engages a disc 124 and causes it to rotate slowly. This disc is provided with a series of circumferentially disposed holes 125 near its periphery to receive one or more pins 126 that may be inserted in selected holes to set up the cycles for reversing the flow through the strainers. These cycles may be in predetermined time periods of say five minutes, ten minutes or intervals to suit the characteristics of the sewage. The disc 124 is provided with a weighted section 127 so that when otherwise released, it will swing back to a zero point so that each new rotation will start at zero to maintain even time intervals. That is, when the time clock motor starts, solenoid 122 is also energized to swing the yoke 123b and thereby engage the friction roller 123 with the disc 124 to set the disc in motion. Should the disc rotate through a time interval less than the predetermined period determined by pin 126 and then the time clock motor stop, the solenoid 122 will be de-energized and the disc will return to zero, when free, so that no accumulative motion is had. In order that the disc may return freely to zero, the contact spring 128 is mounted on a swinging arm 128a which is actuated by the solenoid 122 through a link. When the time clock is operating, this spring 128 is lifted so that a hump of the spring is in the path of the pin 126, and when the pin engages the hump it causes the contactor 128 of the time switch to close the circuit from the transformer, through wire 88 through the wire 129 through contacts 128, 130 and then back through wire 131 to wire 88 leading to solenoid 97, and back through wires 88, 83 to the transformer. In other words, the time clock at predetermined periods, bridges across the terminals of contactor 83 to actuate the four pole switch 102 as frequently as is desired.

In the positions of the parts as shown in Fig. 6, with the switch rod down, the circuit for the solenoid 97 is closed through contactor 83. The solenoid was energized when the float rod reached the bottom of its stroke and opened the pump motor circuit through the contactor 84. The solenoid 97, having been energized, has rotated the bridge 101 of the four pole switch 102 to bridge the contacts for wires 103, 116. The circuit for starter solenoid 108 is open at the four pole switch 105. Now when the float rod is again raised to the top of its stroke, contactor 84 closes the pump motor circuit and contactor 83 opens the circuit controlled thereby, for the solenoid 97, permitting the armature to drop with the pawl 99 in position to engage a tooth of the ratchet wheel 100. The time clock mechanism begins to run as soon as the starter 87 is closed, but it does not have any effect until the pump motor has exceeded its time limit of operation. When the float rod drops it tilts the contacts 83, 84, thereby opening the motor starting circuit and closing the circuit for the solenoid 97 through contactor 83, and the solenoid being energized, the pawl 99 is raised, thereby advancing the ratchet wheel one tooth and swinging the bridge 101 across the poles for the wires 103, 104, thus closing the valve motor starter solenoid 108 through bridge 106 and wire 107. The valve motor is started, turning the valve plug the required distance to reverse the flow.

through the strainers, and as the worm wheel 64 rotates, the roller 67 runs off the arm 68, which falls and tilts the contactor 70, breaking the circuit for the solenoid 113, permitting the pawl to drop into position to engage a tooth of the ratchet wheel 100a. When the worm wheel has made a complete rotation the roller 67 raises the arm 68, which tilts the contactor 70 back to re-establish the circuit for the solenoid 113, which, being energized, lifts the pawl and advances the ratchet wheel 100a one tooth, thereby swinging the bridge 106 across the poles for the wires 116, 107 and opening the circuit for the starter solenoid 108 through the poles for the wires 104, 107, thus stopping the valve motor. This sequence continues so long as the pump motor runs for normal periods of time.

If the pump motor continues to run for a greater period, the time clock mechanism being in operation, the friction roller rotates the disc 124 and carries the pin 126 around until it depresses the spring contact 128 and closes a circuit for the solenoid 97 through contacts 128, 130. The solenoid 97 is then energized and the bridge 101 thrown across the contacts of the four pole switch 102 for wires 103, 116, thereby closing the circuit for the valve motor starter solenoid 108, through wires 90, 103, 116, bridge 106 of the four pole switch 105 (which at this time is bridging the poles for wires 116, 107), then through wire 107, solenoid 108, wires 109 and 93 to the transformer, thereby starting the valve motor 62, which partially rotates the valve plug 39, and at the same time rotates the worm wheel 64, permitting the arm 68 to drop and open the circuit through the contactor 70, thus de-energizing the solenoid 113 and permitting the pawl 115 to drop to a position for engagement with the ratchet wheel 100a. When the worm wheel has been rotated through 360° the roller 67 raises the arm 68, swings the contactor 70 back to the position shown, closing the circuit through wires 90, 111, 112, solenoid 113 and wires 114, 93 back to the transformer, thereby energizing the solenoid 113, which turns the ratchet wheel 100a, one tooth and throws the bridge 106 across the open contacts and opens the circuit for the solenoid 108 through lines 104, 107, thereby stopping the valve motor, until the time clock contacts 128, 130 are again closed by the pin 126, which again closes the circuit for the solenoid 97, which again shifts the bridge 101, thus again closing the circuit through the other contacts thereof, the break in the circuit through the four pole switch 105 having been previously bridged as above set forth. These cycles of valve pump operations continue until the float rod is lowered, breaking the pump motor starter circuit.

The wiring from the main line 85 to the starter 110 for the valve motor 62 preferably includes a main line switch 132 so that the line may be open for servicing the equipment.

In the operation of the pumping apparatus, liquid is admitted to the reservoir through the gate valve 11. The suction flow is through one of the set of pipes 18, 19, check valve 20, J-fitting 22, T 23, strainer 27, elbow hub 31 and through the port 40 or 41, which then connects the elbow hub with the suction side of the pump. Discharge flow is through pipe 47, U-fitting 38, elbow hub 33 and through the port 40 or 41, which then connects the elbow hub 33 with the other elbow hub 31, thence back through the other strainer 27, T fitting 23, through check valve 42, elbow 43, T fitting 44 and thence through the discharge pipe 45. When the valve plug is shifted the flow is

reversed through the strainers, the suction then being through the other set of piping, strainer and valve to the suction side of the pump. High liquid level in the wet well completes the motor circuit for the pump motor and the pump continues to run until the liquid level is lowered to that point where the motor circuit is broken.

If the inflow to the wet well is greater than the pump can dispose of, the time clock mechanism operates to periodically actuate the flow reversing valve so that the strainer will be flushed one or more times during the operation of the pump.

The electrical system shown and described for controlling the operation of the pump motor and the valve motor merely exemplifies one form of means for accomplishing those results. Obviously the time clock control mechanism for the valve motor may be omitted if desired, but it serves to frequently reverse the flow through the strainers in the event that the pump is required to operate continuously or for any considerable period of time, thereby preventing the strainers from becoming clogged. Furthermore, pressure operated means may be substituted for the electrical control mechanism of the apparatus to accomplish the same result. Various other alterations and modifications are possible without departing from the present invention and therefore I do not desire to limit myself to the exact mechanism shown and described, but intend to point out all of the invention disclosed in the appended claims:

I claim as new and novel, and desire to secure by Letters Patent:

1. Pumping apparatus comprising in combination a pump having a suction side and a discharge side, two intake conduits leading from a source of liquid supply, strainers, one in each intake conduit, a discharge conduit communicating with both intake conduits, flow reversing means alternately connecting said intake conduits, through the strainers with the suction side of the pump and simultaneously connecting the discharge side of the pump, alternately, through the strainers, with the discharge conduit, and means operating to periodically actuate said flow-reversing means to thereby reverse the flow through said strainers.

2. Pumping apparatus comprising in combination a pump having a suction side and a discharge side, two intake conduits leading from a source of liquid supply, strainers, one in each intake conduit, a discharge conduit communicating with both intake conduits, a flow-reversing valve having ports connecting either intake conduit, through the strainer with the suction side of the pump and simultaneously connecting the other intake conduit, through its associated strainer, with the discharge side of the pump, and means operating to periodically reverse said flow-reversing means to thereby reverse the flow through said strainers.

3. Pumping apparatus comprising in combination a pump having suction inlet and a discharge outlet, two check valve controlled intake conduits leading from a source of liquid supply, flow reversing means, strainers, one interposed between each intake conduit and the flow-reversing means, the latter having ports simultaneously connecting either strainer with the suction inlet of the pump and the discharge outlet of the pump with the other strainer, means to intermittently actuate said flow reversing means to reverse the flow through the strainers, a discharge pipe and check controlled connections between the discharge pipe and both intake conduits.

4. Pumping apparatus comprising a motor operated pump, two intake conduits leading from a source of liquid supply, a discharge pipe connected with both intake conduits, strainers, one connected with each intake conduit between its intake end and its connection with the discharge pipe, and flow reversing means between both strainers and the inlet and discharge sides of the pump, in combination with means for operating the flow reversing means and responsive to fluctuations of the level of the liquid supply.

5. Pumping apparatus comprising a motor operated pump, two intake conduits leading from a source of liquid supply, a discharge pipe connected with both intake conduits, strainers, one connected with each intake conduit between its intake end and its connection with the discharge pipe, flow reversing means between the strainers and the inlet and discharge sides of the pump, in combination with a motor for operating the flow reversing means, operable connections between said motor and flow reversing means and means responsive to fluctuations of the level of the liquid supply for starting and stopping the pump motor.

6. Pumping apparatus comprising a motor operated pump, intake conduits leading from a source of liquid supply, a discharge pipe connected with both intake conduits, strainers, one connected with each intake conduit, and flow reversing means between the strainers and the suction and discharge sides of the pump, in combination with a motor for operating the flow reversing means, operable connections between said motor and flow reversing means, means responsive to fluctuations of the level of the liquid supply for starting and stopping the pump motor, and mechanism controlled by said last mentioned means to start the motor for the flow reversing means, said mechanism including means to stop the last mentioned motor.

7. Pumping apparatus comprising in combination a pump having a suction side and a discharge side, a pump motor therefor, two sets of intake piping leading from a single source of liquid supply, strainers, one in each set of piping, flow-reversing means interposed between the strainers and the suction side and discharge side of the pump, electrical control means responsive to fluctuation of the level of the liquid supply for starting and stopping the pump motor, electric motor operated means to operate said flow-reversing means, electrical control means operating subsequently to the stoppage of the pump motor to start the motor of the flow-reversing means, and discharge piping in communication with the two sets of intake piping and the strainers.

8. Pumping apparatus comprising in combination a pump having a suction side and a discharge side, a pump motor therefor, two sets of intake piping leading from a single source of liquid supply, strainers, one in each set of piping, a flow-reversing valve interposed between the strainers and the suction side and discharge side of the pump, electrical control means responsive to fluctuations of the level of the liquid supply for starting and stopping the pump motor, electric motor operated means to operate said valve to reverse the direction of flow through the strainers, electrical control means responsive to the low level of the liquid supply for starting the

motor of the valve operating means, electrical control means to stop said valve motor, and a discharge pipe in communication with the two sets of intake piping and strainers.

9. Pumping apparatus comprising in combination a motor driven pump having a suction side and a discharge side, two check valve controlled intake pipes leading from a fluctuating source of liquid supply, each pipe having two branches, strainers, one connected to one branch of each pipe, a flow reversing valve having a casing provided with connections with the suction side and discharge side of the pump and with the two strainers, and a four-way valve plug in said casing, having ports for connecting either strainer with the suction side of the pump and simultaneously connecting the other strainer with the discharge side of the pump, whereby the flow through the strainers may be reversed upon rotation of the valve plug, a discharge pipe having check valve controlled connections with both intake pipes, motor operated means to periodically actuate the valve plug, said means being responsive to fluctuations of the levels of the source of liquid supply and means to start and stop the pump motor controlled by fluctuations of the level of the liquid supply.

10. Pumping apparatus comprising in combination a motor driven pump, intake pipe lines leading from a source of liquid supply, a strainer in each pipe line, flow reversing means interposed between the strainers and the suction side of the pump, and between the discharge side of the pump and strainers, a discharge pipe having connections with each intake pipe line, starting and stopping means for the pump motor, responsive to fluctuations of the level of the liquid supply, and means for periodically actuating the flow reversing means for reversing the direction of the flow through the strainers.

11. Pumping apparatus comprising in combination a motor driven pump, intake pipe lines leading from a source of liquid supply, a strainer in each pipe line, flow reversing means interposed between the strainers and the suction side of the pump, and between the discharge side of the pump and strainers, a discharge pipe having connections with each intake pipe line, starting and stopping means for the pump motor, responsive to fluctuations of the level of the liquid supply, and means for periodically actuating the flow reversing means for reversing the direction of the flow through the strainers, said last mentioned actuating means being responsive to the pump motor starting and stopping means.

12. Pumping apparatus comprising in combination a motor driven pump, intake pipe lines leading from a source of liquid supply, a strainer in each pipe line, flow reversing means interposed between the strainers and the suction side of the pump, and between the discharge side of the pump and strainers, a discharge pipe having connections with each intake pipe line, starting and stopping means for the pump motor, responsive to fluctuations of the level of the liquid supply, and means for periodically actuating the flow reversing means for reversing the direction of the flow through the strainers, and time controlled mechanism for periodically starting and stopping the actuating means for the flow reversing means.

ALFRED CHARLES PAGE.
